UNITED STATES PATENT OFFICE.

CHARLES FLECKENSTEIN, OF PORTLAND, OREGON.

FRUIT-DRIER.

SPECIFICATION forming part of Letters Patent No. 584,818, dated June 22, 1897.

Application filed March 2, 1896. Serial No. 581,569. (No model.)

To all whom it may concern:

Be it known that I, CHARLES FLECKENSTEIN, a citizen of the United States, residing at Portland, in the county of Multnomah, 5 State of Oregon, have invented a certain new and useful Improvement in Fruit-Driers, of which the following is a specification, reference being had to the accompanying drawings.

10 My invention relates to fruit-driers in which the trays are stacked on top of each other to cause heated air to ascend through the fruit placed upon each tray; and the objects of my improvement are to provide simple and 15 inexpensive means to lift one end of the whole stack of trays except the bottom tray, and means to advance outwardly said bottom tray to permit the removal of the latter with speed and convenience. I attain these objects by 20 the construction illustrated in the accompanying drawings, in which—

Figure 1 is a longitudinal vertical central section of the lower portion of the fruit-drying compartment, having trays therein and means 25 to facilitate the removal of the lowest tray in accordance with my invention. Fig. 2 is a transverse vertical section of the same through line x y of Fig. 1. Fig. 3 is a longitudinal vertical section, on a larger scale 30 than Fig. 1, of the lower portion of the fruit-drying apparatus and trays, showing the improved hook and the lower tray removed.

This is an improvement upon the construction shown in the application for patent made 35 by Adam Fleckenstein, February 24, 1896, Serial No. 580,585, mainly to dispense with one of the lifting hooks and levers, this drier being also intended to be provided with a tray-feeding door near the top and a discharge-door at one end near the bottom.

The walls of the fruit-drying compartment C are substantially air-tight and rest upon the walls of the hot-air chamber A. The compartment C is preferably made to hold about 45 fifty trays of about the size of eighteen by forty-two inches. The interior of said compartment is about said size, so that the walls serve to guide the trays when descending or slightly ascending therein.

50 To facilitate the removal of the lowest tray T', a roller R, preferably as long as the width

of the trays, is located in the back end and lower corner of the compartment C, its spindle being mounted in bearings secured to the walls of said compartment at such height 55 that the upper part of its periphery is on a level slightly higher than the upper edge of the tray T'. The front portion of said tray T' rests upon a small roller r, having its bearings mounted also in the walls of the compartment C.

At the front end of the exterior of the compartment C, near the bottom thereof, there is pivotally mounted a lever L in bearings placed upon a timber b, having its ends resting upon blocks mounted upon the walls of the hot-air chamber A, and a small door D under the timber b closes the lower portion of the front end of the compartment C. To the lever L is attached one end of a chain h², 65 having on the opposite end the rectangular upper link h³ of the hook h. The hook and its shank are thus made of two pieces hinged together so that the upper link, that cannot rotate, and a portion of the chain can be made 70 to slide up and down in a recess cut in the inner face of the timber b, while the hook proper, h, can be made to swing on its hinge out and in engagement with the bottom of the tray if the attendant opens the small door 75 D or uses, through a vertical slot, a hooked rod for engagement with the knob or handle k on the rear face of the hook h, the latter means being preferred, so as to let out as little hot air as possible from the compartment C.

To remove the bottom tray T', the free end of the lever L is depressed, and thus the front end of the tray T², Fig. 1, is slightly lifted, and with it the other trays T. The door D is 90 then opened, and as the back end of the tray T' rests upon the inclined surface of the roller R and the other trays are bearing upon said back end the tray T' will obtain a forward impetus to push it partly over the small roller 95 r and through the open end door D far enough to be easily grasped and removed. The top surface of the roller R is only about one-sixteenth of an inch higher than the top of the tray, so that when the tray T² has taken the 100 place of the tray T', as in Fig. 3, with its front end abutting against the door D, the

hook *h* is then free to swing back and again made to engage in the opening *o* in the bottom of the overlying tray. If it is desired to examine the contents of the lower tray while 5 pulled half-way out, the height of the door should not be much more than the height of the tray, as shown by the dotted line *a* in Fig. 2, so that the wall of the casing will oppose the thrust caused by the roller *R* on the 10 back end of the tray.

Having now fully described my invention, I claim—

1. In a fruit-drier the combination of the walls of the compartment *C* having a door in 15 one of its narrow sides, a series of superposed trays fitted within said walls, a lever pivoted above said door, a chain and hook pendent from said lever, and a roller *R* in the rear end of the drier, the top surface of said roller 20 being above the floor of the drier a distance

slightly higher than the thickness of one of the trays substantially as described.

2. In a fruit-drier the combination of the walls of the compartment *C* having a door in the bottom of its front end, a series of super- 25 posed trays fitted within said walls, a lever pivoted above the bottom door, a chain and long link pendent from said lever, a hook hinged to said link, a roller *r* on the front end of the drier-floor, and a roller *R* in the 30 rear end projecting above the floor substantially as described.

In testimony whereof I affix my signature, in the presence of two witnesses, this 21st day of February, 1896.

CHARLES FLECKENSTEIN.
